United States Patent Office

Des. 222,395
Patented Oct. 19, 1971

222,395

PIANO

Winsor D. White, Jr., Blowing Rock, N.C., assignor to
D. H. Baldwin Company, Cincinnati, Ohio

Filed Nov. 16, 1970, Ser. No. 26,024

Term of patent 14 years

Int. Cl. D17—01

U.S. Cl. D56—9

FIG. 1

FIG. 2FIG. 3

FIG. 1 is a left side, top and front perspective view of a piano, showing my new design;

FIG. 2 is a front elevational view; and

FIG. 3 is a side elevational view, the opposite side being substantially a mirror image thereof.

The back, not shown, is conventional.

I claim:

The ornamental design for a piano, substantially as shown and described.
